UNITED STATES PATENT OFFICE.

EDWARD KELLS, OF CLEVELAND, OHIO.

FAUCET AND FILLER.

SPECIFICATION forming part of Letters Patent No. 336,721, dated February 23, 1886.

Application filed October 12, 1885. Serial No. 179,599. (No model.)

To all whom it may concern:

Be it known that I, EDWARD KELLS, of Cleveland, in the county of Cuyahoga and State of Ohio, have invented a certain Improved Faucet and Filler Combined, the nature of which consists in providing the can with a removable cap, which is connected with an opening through which the fluid is poured into the can, and is closed by said cap when required. Attached to the said cap is a peculiarly constructed faucet having a tubular rotary stem in open relation with the interior of the can. The stem is packed within a casing of tubular or other proper form, and provided with a screw-gland for the purpose of acting upon the compressible packing, to prevent leakage of the faucet, and, in connection with a handle, arrests lateral displacement of the tubular stem and packing.

In the transportation and handling packages of hydrocarbon oils or fluids it is very important that every suitable means be employed to prevent leakage of the faucet, for well-known reasons. For this purpose is designed the said invention.

That the said invention may be more fully seen and understood, reference will be had to the following specifications and to the annexed drawings, making part of the same, in which like letters denote like parts in the several views.

Figure 1 is a front view of the said invention, showing it attached to a can. Fig. 2 is a side view of the same, and Fig. 3 a longitudinal vertical section.

In the drawings, A represents the can, which may be of any suitable form and capacity for the purpose designed. To the top of the can is secured, by soldering or otherwise, the threaded collar B, to which is fitted the screw-cap C, Figs. 1 and 2. The faucet D is attached to the said cap, as seen in the drawings, and consists of the cylinder or casing E, which may be of any suitable form, having an interior lining, F, of cork, leather, or other material adapted to the purpose designed. It is considered preferable to have the said gland screwed on the tubular stem H of the faucet, as seen in Fig. 3. It will be noted that the way I of the stem H is open to the outlet J, which outlet is shown in the drawings as being closed by the packing F when the stem is in the po-

sition shown in Fig. 1. This position of the stem effectually cuts off the passage of fluid from the can, as the throat K, which forms the passage from the interior of the can to the way I, is closed by the stem, as shown. On turning the handle L of the head M, so that the outlet J will be in open relation with the throat K, the oil or fluid will then be allowed to flow out of the can through the opening N, Fig. 3, throat K, outlet J, and the way I, in the stem H, on tipping the can, so that the fluid may escape. The flow is readily cut off by turning back the handle to the position shown in Fig. 1, which closes the throat K and prevents the outflow.

A tight and unleaking faucet is attained in part by means of the packing F, which is placed within the bore of the casing or cylinder E. One end of this packing is in contact with the head M, to which the tubular stem H and handle L are attached, and the other end of the said packing butts against the inner end of the gland G, as seen in Fig. 3. The only way of leakage from the faucet is the passage through the throat K, which is closed up by the stem H when the faucet is shut, as in Fig. 3.

In case of leakage the packing may be so compressed around the stem within the casing, by screwing in the gland G, as to prevent leakage.

To fill the can, the screw-cap C is removed with the faucet. The fluid may then be poured through collar B and opening N in the can. The cap C is then replaced by being screwed down over the collar to its place, as seen in the drawings. Packing may be used in connection with the collar and cap, if needed to make a tight joint. By means of the gland G the stem H is prevented from being forced out of its place within the packing and casing, and also by its action the packing is made close and compact about the stem, to form a tight joint.

In case the collar B and cap C are not required upon a can, but only the faucet, it may be attached to a can by soldering or otherwise, and will then be used for the same purpose of drawing off the fluid, as hereinbefore described.

What I claim as my invention, and desire to secure by Letters Patent, is—

In combination with an oil-can, a combined
filler and faucet consisting of the collar B and
cap C, detachably connected to said collar,
cylinder E, provided with a flexible lining,
5 tubular stem H, arranged in cylinder E and
having opening J communicating with throat
K, leading to the interior of the can, and hav-
ing at one end a head and handle, L, and
gland G, screwed on one end of the tubular

stem, substantially as described, and for the 10
purposes specified.

In testimony whereof I affix my signature in
presence of two witnesses.

EDWARD KELLS.
